UNITED STATES PATENT OFFICE.

JACOB SHAPIRO, OF BROOKLYN, NEW YORK.

AUTOMATIC STOP FOR SEWING-MACHINES.

1,332,071.

Specification of Letters Patent. Patented Feb. 24, 1920.

Application filed April 23, 1919. Serial No. 292,012.

To all whom it may concern:

Be it known that I, JACOB SHAPIRO, a citizen of the United States, and a resident of the city of New York, borough of Brooklyn, in the county of Kings and State of New York, have invented a new and Improved Automatic Stop for Sewing-Machines, of which the following is a full, clear, and exact description.

10 This invention relates to automatic stops, and particularly to a stop for sewing machines and has for an object the provision of means which will automatically operate upon the breaking of the thread of the sewing machine to throw off the driving power of the machine.

Another object of the invention is to provide a mechanism operated by certain parts of the sewing machine for throwing off the power when the thread of the sewing machine has been broken.

A further object, more specifically, is the provision of a clutch throwing mechanism operated by a positive movement from certain of the driven elements of the sewing machine when the same are connected thereto.

In the accompanying drawings:

Figure 1 is a side view showing part of 30 the sewing machine with an embodiment of the invention applied thereto.

Fig. 2 is a fragmentary sectional view through Fig. 1 on line 2-2, the same being on an enlarged scale.

Fig. 3 is a view similar to Fig. 2, but showing the parts in a different position.

Fig. 4 is a view similar to Fig. 1, but showing the parts in an operated position.

Fig. 5 is an end view of part of the sewing machine shown in Fig. 4, disclosing the arrangement of levers and clutch.

Fig. 6 is an enlarged fragmentary sectional view showing the connection between certain of the driven parts of the sewing machine and the clutch releasing mechanism.

Referring to the accompanying drawings by numerals, 1 indicates a sewing machine which may be of any desired type and which is provided with a driving clutch 2 (Fig. 5) operated by a belt 3, said cable being capable of movement into and out of engagement with a suitable clutch face arranged on the pulley 4 operating the belt 5 passing over the pulley 6 operating the mechanism 55 of the sewing machine. A pivotally

mounted bell crank lever 7 is connected in any suitable manner with the clutch pulley 2 and is thrown into and out of engagement by the operation of an adjustable operating bar structure 8, which is preferably made in two sections and clamped together. This bar section is pivotally connected with the lever 9 carrying a chain 10 at the upper end. This chain is connected to a swinging arm 11 pivotally mounted on the sewing machine 1 and operated by a plate or bar 12. This bar or plate is provided with a notch 13 and with an upstanding portion 14 having a slot 15. Extending through the slot 15 is a pin 16 which is formed integral with or rigidly secured to a sleeve 17. This sleeve 17 is clamped by any suitable means, as for instance set screw 18 to a rod 19 journaled in the turned over ears or plate 20, also in part of the head 21 of the sewing machine. The end of the rod 19 on the face of the head 21 is provided with a bent up portion 22 and a curled or looped portion 23 through which the thread 24 passes. The sewing machine is provided with any usual or preferred form of tension means forming no part of the present invention, in order that the line of stitching may be drawn properly and this tension means naturally holds the thread 24 substantially in a straight line and substantially supports the portion 22 and the eyelet or looped portion 23. As the thread supports these parts it also holds the rod 19 in a given position which normally maintains the pin 16 in its elevated position illustrated in Figs. 1 and 2. When the pin is held in this manner in its elevated position it will in turn hold the plate 12 in the position shown in Fig. 1 whereby the pin 25 connected to arm 26 will be out of contact with the plate 12 and though it swings back and forth under the action of the sewing machine it will merely act as an idler. In order to cause the arm 26 to swing in the manner just described it is rigidly secured to a shaft 27 which carries the arm 28, which arm is provided with a pin 29 acting in a cam groove 30, arm 28 and associate parts forming no part of the present invention, *per se*, as they are old and well known and are used in reciprocating member 31 also old and well known. The arm 26 is merely connected with these parts in order to be continually moved back and forth as the sewing machine operates, 110

- so that in case the thread 24 should break the rod 19 would be allowed to rotate under the action caused by gravity acting on rod 19 which in turn acts on the pin 16.
- 5 When the plate 12 is allowed to drop down in this manner the pin 25 on arm 26 will strike against the shoulder 32 and will strike a quick sudden blow and will quickly move over the plate 12 and chain 10 as well
- 10 as the parts associated therewith whereupon the clutch member 2 is unclutched and the power is thereby thrown off of the machine. Usually the blow of pin 25 against shoulder 32 is sufficient to cause the parts to assume the loose position shown in Fig. 4. The clutch will naturally remain unclutched until positively moved back into clutching position, which may be done in any desired manner, as for instance by working the lever 9. Before this is done, however, the thread 24 is properly adjusted and passed through the needle so as to be ready for proper sewing operation. It is to be noted that the arm 26 swings continually during
- 15 the operation of the sewing machine while the plate 12 and parts connected therewith remain idle until the thread breaks whereupon it will immediately operate to throw off the power.
- 20 What I claim is:
1. The combination with a power driven sewing machine provided with a clutch for throwing the power on and off, of a lever associated with said clutch for shifting the same, a flexible member connected with said lever, a plate connected with said flexible member, a constantly swinging arm operated by the mechanism of the sewing machine arranged adjacent said plate and adapted to
- 25 move the plate, flexible member and lever for unclutching said clutch when the plate has been moved downwardly a predetermined distance under the action of gravity, and means normally held in a given position by the thread of the sewing machine for holding the plate in an elevated position.
- 30 2. The combination with a power driven sewing machine having a clutch, of means for throwing the clutch into and out of engagement, said means including a system of levers, a flexible member, a swinging arm having one end connected with the flexible member, a plate pivotally mounted on said swinging arm, said plate having an elongated notch therein, means for supporting the plate so as to prevent its downward swinging movement under the action of gravity, means controlled by the thread of the sewing machine for holding the supporting means of the plate in a given position, and a swinging power arm actuated by the mechanism of the sewing machine arranged beneath said notch and adapted to strike one end of the plate in the notch when
- 35 the plate is moved down under the action

of gravity a predetermined distance whereby said flexible member and parts associated therewith will be pulled for moving the clutch to an unclutched position.

3. The combination with a power driven 70 sewing machine provided with a clutch of means for automatically stopping the machine when the thread breaks, said means comprising a pivotally mounted rod having an upstanding portion formed with an eyelet through which the thread passes, said thread acting to hold the rod against rotary movement when the thread is moving in its normal path and to permit the rod to move under the action of gravity when the thread 80 is broken, a pin connected with said rod, a pivotally mounted plate formed with a slot through which said pin projects whereby one end of said plate is supported by said pin, said plate having a shoulder, a swinging arm actuated by the mechanism of the sewing machine, said arm being arranged below said shoulder and adapted to strike said shoulder when said pin is moved pivotally downwardly for allowing the plate to 90 swing downward whereby the plate is caused to move quickly and open said clutch.

4. The combination with a sewing machine having a clutch for connecting power thereto of means for disconnecting said power, 95 said means comprising a plurality of members for moving said clutch to an open position, said members including a flexible member, a swinging arm connected with one end of the flexible member, a swinging plate pivotally mounted on the swinging arm, said plate having an elongated notch, a swinging power arm having a pin adapted to fit into said notch when said plate moves downwardly under the action of gravity whereby 105 the plate will be pulled and said flexible member will be pulled for unclutching said clutch, a pin engaging said plate for normally preventing its downward movement under the action of gravity, and a control 110 rod connected with said pin for holding the same in a given position, said pin having a guide through which the thread of the sewing machine passes and which holds the control rod normally in a given position.

5. The combination with a power driven sewing machine having a clutch of automatic means for throwing out said clutch, said means including a flexible member, mechanism for connecting one end of the flexible member with the clutch, a swinging arm connected with the opposite end of the flexible member, a plate pivotally mounted on said frame, said plate having a notch, a slot, a swinging power member having a pin adapted to fit into said notch and thereby move the plate when the plate moves under the action of gravity to a given position, a pin extending through said slot for normally holding said plate in an elevated 125 130

position against the action of gravity, and a control rod rigidly secured to said pin, said control rod having an upwardly extending portion and an eyelet thereon for holding a thread whereby when said thread is moving in its regular course the parts will be held in an operative position, and when

the thread breaks the weight of said parts will cause said rod to rotate a sufficient distance to permit said plate to drop under the action of gravity until it engages the pin on the power arm.

10
JACOB SHAPIRO.
